Virzi

[11] Patent Number: Des. 364,330

[45] Date of Patent: **Nov. 21, 1995

[54] SLIDING PANELS SECURITY DEVICE

3,615,114 10/1971 Harris ..... D8/339 X
4,397,499 8/1983 Work et al. ..... 292/259 R

[75] Inventor: Al Virzi, Troy, Mich.

Primary Examiner—Brian N. Vinson

[73] Assignee: G&D Communications Corporation,
Bloomfield Hills, Mich.

[57] CLAIM

[**] Term: 14 Years

The ornamental design for a sliding panels security device,
as shown and described.

[21] Appl. No.: 20,180

DESCRIPTION

[22] Filed: Apr. 14, 1994

FIG. 1 is a top, front, and left side perspective view of a
sliding panels security device showing my new design, the
broken-line disclosure of a portion of a set of sliding panels
being for illustrative purposes only and forming no part of
the claimed design;

[52] U.S. Cl. D8/341

FIG. 2 is an enlarged top plan view thereof, the bottom being
identical in appearance; and,[58] Field of Search D8/330-331, 339,
D8/341; 70/77, 89, 90, 95, 97-98; 292/289,
292-294, 259 R, DIG. 20, DIG. 46FIG. 3 is an enlarged left side elevational view thereof, the
right side being a mirror image of that shown.
